US0D1008827S

(12) **United States Design Patent** (10) Patent No.: **US D1,008,827 S**
(45) Date of Patent: ** Dec. 26, 2023

(54) **THERMOMETER FOR DOUGH PROOFING TRAY**

(71) Applicant: **Gozney Group Limited**, Christchurch (GB)

(72) Inventors: **Ryan Breeze**, Bournemouth (GB); **James William Kirk**, Bournemouth (GB); **Thomas Robert Llewelyn Gozney**, Bournemouth (GB)

(73) Assignee: **Gozney Group Limited**

(**) Term: **15 Years**

(21) Appl. No.: **29/851,149**

(22) Filed: **Aug. 25, 2022**

Related U.S. Application Data

(63) Continuation of application No. 29/850,284, filed on Aug. 18, 2022.

(57) **CLAIM**

The ornamental design for a thermometer for dough proofing tray, as shown and described.

DESCRIPTION

The sole FIGURE is a plan view of a top surface of a thermometer for a dough proofing tray showing our new design.

The broken line showing of portions of the thermometer in the sole FIGURE represents environmental subject matter and forms no part of the claimed design.

The bottom, front, rear, left side, and right side, views are omitted and form no part of the claimed design.

1 Claim, 1 Drawing Sheet
